UNITED STATES PATENT OFFICE

PETER C. BRUCKMANN AND WILLIAM R. HAGER, OF ST. LOUIS, MISSOURI, ASSIGNEES,
BY MESNE ASSIGNMENTS, TO VORCLONE CORPORATION, OF MILWAUKEE, WISCONSIN, A CORPORATION OF DELAWARE

LAUNDRY-DRUM CONSTRUCTION

Application filed October 28, 1928. Serial No. 144,837.

This invention pertains to laundry drum construction. The ordinary commercial laundry drum is of cylindrical shape and composed of wooden parts which are alternatively soaked and dried. Consequently such parts are subjected to expansion and contraction which loosens the several joints between the parts.

Therefore, it is one of the objects of this invention to provide a construction which will provide a secure fastening for the various parts and one which may be taken up to prevent looseness.

Another object is to provide a structure which will securely hold the ribs in place and in their proper relation with the end faces.

Another object is to provide an adjustable bracing structure which is simple and economical to construct and easy to install.

Further objects will appear from the following description, taken in connection with the accompanying drawing, in which

Figure 1 is an end view of a laundry drum embodying this invention;

Figure 2 is a partial section somewhat enlarged, taken on line 2—2 of Figure 1; and

Figure 3 is a detail section showing the construction of the braces.

The laundry drum shown in the drawing is constructed of a series of slats 1, which run lengthwise of the drum, and are shown only in end view in Figure 1. These are secured in any suitable manner to the rim of an end face 2 and are ordinarily held in place by a band or hoop 3. The slats and the end face 2 are usually constructed of wood. The end face may be constructed of a series of transverse boards which may be spaced from each other, as illustrated in Figure 1, so as to provide for

expansion and contraction. At spaced points around the circumference of each end face radial recesses are provided to receive the ribs 4 which are let into those recesses so as to project inwardly from the surface of the drum. These ribs may be extended longitudinally so as to protrude a short distance outside of each end face 2, as illustrated in Figure 2.

In accordance with the present invention, each end face 2 has mounted thereon a face

plate 5 of cast iron, steel, or other suitable material. This face is usually provided with a suitable trunnion on which the drum may rotate and may be provided with a coupling member 6 for driving the drum. The face plate 5 may be bolted to the end face by bolts 7 or other suitable fastening.

Arranged around the periphery of the end face and radially outside of the face plate 5 is a series of braces 8. These braces are provided with suitable bolt holes 9, which may be elongated to provide for adjustment, and through which bolts 10 may be passed for securing the braces to the end face 2. The braces 8 are arcuate in form and are provided with terminal abutments 11 adapted to engage the protruding end of the rib 4. Each brace 8 bridges the interval between adjacent ribs and bears against those ribs at its ends. The abutments 11, which bear against the ribs, are slotted radially so as to provide sockets 14 for the legs of a U-bolt 12 which provides a tension member for clamping the braces against the sides of the ribs. The closed end of the U-bolt is hooked over a lug 13 on the face plate 5. There are a number of lugs 13 corresponding with the number of ribs and spaced around the rim of the face plate 5, as shown in Figure 1. The legs of the U-bolt 12 extend through the sockets 14 and are provided at their outer ends with clamping nuts 15, bearing against collars 16 which rest upon the outside of the braces 8. It will be seen that by drawing up on the nuts 15 the braces 8 may be drawn inwardly so as to clamp the ribs 4 securely therebetween. The braces are tensioned to the face plate 5 so as to provide a rigid driving structure.

It will be seen that this invention provides a very simple construction for laundry drums and one which is very rigid and in which the effects of expansion and contraction may be compensated for by readjustment. The braces 8 may be kept securely clamped against the ribs so that said ribs are always securely held in place and connected rigidly with the face plate 5 so that the drum may be driven from the face plate 5 and the ribs 4.

It is obvious that various changes may be

made in the details of construction without departing from the spirit of this invention; it is to be understood, therefore, that this invention is not limited to the specific details shown and described.

5 Having thus described the invention what is claimed is:

1. In a laundry drum including an end face and ribs removably carried thereby, a 10 face plate secured to the end face, braces movable radially of said face plate and engaging the ribs on opposite sides thereof, and tension members anchored to said face plate engaging the braces to draw said braces inwardly.
- 15 2. In a laundry drum including an end face and ribs removably carried thereby, a face plate secured to the end face, braces bridging the intervals between ribs and having terminal sockets, and tension members in said sockets and engaging said face plate.
- 20 3. In a laundry drum including an end face and ribs removably carried thereby, a face plate secured to the end face, braces bridging the intervals between ribs and having terminal sockets, ears on said face plate, and U-bolts in said sockets and engaging said ears adapted to tension said braces to clamp the ribs.
- 25 30 4. In a laundry drum, the combination with an end face, of ribs projecting from and removably carried by said face, lugs carried by the end face, braces carried and movable radially of said end face, said braces engaging the sides of the ribs, and bolts engaging the lugs and the ends of said braces to draw the latter into clamping contact with the projecting ends of the ribs.
- 35 40 5. In a laundry drum, the combination with an end face, of ribs projecting from and removably carried by the end face, braces carried by and movable radially of said end face, said braces engaging the sides of the ribs, and means for engaging the end face and said braces to draw the latter into clamping contact with the ribs.

In testimony whereof we affix our signatures this 2nd day of August, 1926.

PETER C. BRUCKMANN.

WILLIAM R. HAGER.
